CLAIM

The ornamental design for a portion of a sandal, as shown and described.

DESCRIPTION

FIG. 1 is a perspective view of a portion of a sandal, showing my new design;

FIG. 2 is a right side elevation view thereof;

FIG. 3 is a left side elevation view thereof;

FIG. 4 is a front view thereof;

FIG. 5 is a rear view thereof;

FIG. 6 is a top plan view thereof;

FIG. 7 is a bottom plan view thereof;

FIG. 8 is a right side elevation view of another embodiment of a portion of a sandal, shown in FIG. 1; and,

FIG. 9 is a close up view of the fastener shown in FIGS. 1–8. The broken line showing of the heel, interchangeable top, and sandal top is included for the purpose of illustrating environmental structure and forms no part of the claimed design.
